UNITED STATES PATENT OFFICE.

JACOB RACICH, OF NEW YORK, N. Y.

RATCHET-DRILL.

SPECIFICATION forming part of Letters Patent No. 596,910, dated January 4, 1898.

Application filed June 22, 1897. Serial No. 641,841. (No model.)

To all whom it may concern:

Be it known that I, JACOB RACICH, of New York city, in the county and State of New York, have invented a new and Improved 5 Ratchet-Drill, of which the following is a full, clear, and exact description.

My invention relates to an improvement in portable drills operated by ratchet mechanism; and it consists in certain improvements 10 by which the drill is operated while the handle is being moved in either direction.

The object of the invention is to provide drills of this character with mechanism which will rotate the drill while the handle is being 15 moved in either direction, and also to provide such mechanism which will be of greater power than that commonly used for this purpose.

The invention consists of certain details 20 which will be more particularly pointed out in the following specification and claims.

Reference is to be had to the accompanying drawings, forming a part of this specification, in which similar characters of reference indicate 25 corresponding parts in all the views.

Figure 1 is a side elevation of the device. Fig. 2 is a sectional elevation thereof. Fig. 3 is a plan view taken on the line 3 3 of Fig. 1. Fig. 4 is a similar view taken on the line 4 4 30 of Fig. 2. Fig. 5 is a section taken upon the line 5 5 of Fig. 2, and Fig. 6 is a section on the line 6 6 of Fig. 2.

The drill S is secured in any suitable manner within the socket A. In the drawings I 35 have shown a thumb-screw a for securing the drill in place. Any mechanism for this purpose may, however, be used, as this feature forms no part of my invention. The socket A has a central bar A' extending above the 40 same and entering a hole in the sleeve E, and to the bar A' is attached the ratchet-wheel C by any suitable means.

Immediately above the ratchet-wheel C and separated therefrom by the balls C', forming 45 an antifriction-bearing, is a plate D, which extends to one side and upon which is mounted the fulcrum for the operating-lever. Upon the upper side of the plate D a collar A² is fixed to the bar A', thus preventing the plate 50 and the ratchet-wheel from separating sufficiently to allow the balls C' to drop out of

their groove. To the upper surface of the plate D is also attached by screws d the flange d' of a sleeve D². The inner surface of the sleeve D² and the outer surface of the sleeve 55 E are correspondingly threaded, one screwing within the other, and these threads should be left-handed in order that the rotation of the drill may be utilized to feed the same when desired. For this purpose the inner 60 sleeve E is longitudinally slotted upon one side, as shown by dotted lines at e' in Fig. 2 and also in Fig. 5.

The upper end of the stem A' has a hole e², 65 adapted to receive a pin e³, which may be inserted through the slot e', thus locking the stem and sleeve together and causing the sleeve to rotate with the stem A'. The upper end of the sleeve E is enlarged into a toothed head E', which has a series of radial 70 holes e, which may be engaged by a pin to feed the drill by hand, if desired. The upper surface of the head E' is provided with a circular groove adapted to receive the balls J², which lie between this head and the foot 75 J' of the arm J, said head and foot being held together by a central screw J³. The upper surface of the foot J' is preferably roughened in order that it may securely engage any substance against which it may be placed in use. 80

The plate D upon its outer end has a sleeve D' attached to or formed as a part thereof and extending parallel to the sleeves E and D²—that is, parallel with the axis of the drill. Within the sleeve D' is a second sleeve F, to 85 the lower end of which is secured, by means of a bolt f, the head B of the operating-handle B'. These two parts may be made integral, or, as shown in the drawings, the handle B' may consist of a pipe screwing upon 90 the head B. Preferably the lower end of the sleeve F is somewhat reduced, forming a journal F' for the reception of the head B, which is secured to the journal F' by means of a key f' or other suitable fastening device. 95 The head B has two pivots B² and B³ located upon each side of its center line and between the pivot F' and the axis of the drill. To these pivots B² and B³ are pivoted pawls or dogs b b', provided with springs b², holding 100 their outer ends against the ratchet-wheel C.

It will thus be seen that one of the pawls

or dogs b b' will operate to turn the ratchet-wheel in whichever direction the handle is moved. When the handle is moved in one direction, the dog b will engage the ratchet-wheel to turn it, and when the handle is moved in the opposite direction the dog b' will engage the ratchet-wheel to turn it while the other dog is being withdrawn for a new hold. These dogs in their operation act on the same principle as a toggle-joint, thus producing a powerful actuating mechanism.

The sleeve F contains a rod G , which is centrally slotted at G' throughout a greater portion of its length. Within the slot G' extends a pin g , which also passes through the flange upon the upper end of the sleeve F , thus locking the sleeve and rod together, but permitting their extension. To the upper end of the rod G is attached a lever H by means of a set-screw H^2 or any other suitable device. The projecting arm of the lever H is provided with a slot H' , and a dog or pawl I is secured therein by means of a thumb-screw h . The pawl I has its outer end held in engagement with the toothed head E' by means of a spring I' . As the sleeve F oscillates at each oscillation of the handle B' , the arm H will oscillate in a similar manner. The pawl I , engaging the teeth upon the head E' , will operate to turn the same, and thus to actuate the feed by revolving the sleeve E . The amount of this revolution may be regulated by adjusting the location of the thumb-screw h . When the thumb-screw is moved to the outer end of the slot H' , the feed will be greater than when it is moved close to its inner end. In this manner the feed may be regulated to any desired extent. The feeding may be done either by hand, using a pin which is made to engage the holes e in the head E' , automatically by using the arm H and pawl I , or by locking the stem A' and the sleeve E together by means of the pin e^2 . It is therefore possible to secure considerable variation in the rate of feed, and the device may be set at such feed as is best adapted to the particular circumstances.

It is evident that the mechanism herein described for rotating the drill may be utilized for rotating shafts where it is desired to use the oscillating motion of a lever. It secures a nearly constant rotation of the shaft and enables considerable power to be applied for this purpose, due to the toggle-joint structure formed by the head B and the dogs b and b' .

Having thus described my invention, I claim as new and desire to secure by Letters Patent—

60 1. A ratchet-drill-operating mechanism, comprising a ratchet-wheel connected to the drill-socket, an operating-lever pivoted at one side of the axis of the drill, double pawls pivoted to said lever upon opposite sides of its centerline, and a positively-operating adjustable feed mechanism actuated from said lever, substantially as described.

65 2. A ratchet-drill-operating mechanism, comprising a ratchet-wheel connected to the drill-socket, an operating-lever pivoted at one side of the axis of the drill, double pawls pivoted to said lever upon opposite sides of its centerline, a back-pressure foot, a threaded cylinder and sleeve, one engaging the drill-socket and the other the back-pressure foot, and means for rotating either the cylinder or the sleeve from a handle-lever, substantially as described.

3. A ratchet-drill-operating mechanism, comprising a ratchet-wheel connected to the drill-socket, an operating-lever pivoted at one side of the axis of the drill, double pawls pivoted to said lever upon opposite sides of its centerline, a back-pressure foot, threaded sleeves, one engaging the drill-socket and the other the back-pressure foot, a toothed feed-wheel upon one of said sleeves, and a pawl engaging said feed-wheel and operated from a handle-lever, substantially as described.

4. A ratchet-drill-operating mechanism, comprising a ratchet-wheel connected to the drill-socket, an operating-lever pivoted at one side of the axis of the drill, double pawls pivoted to said lever upon opposite sides of its centerline, a back-pressure foot, threaded sleeves, one engaging the drill-socket and the other the back-pressure foot, a toothed feed-wheel connected to the latter, a telescopic rod connected to the handle and the back-pressure foot, a slotted arm carried by the outer section of said rod, and a pawl adjustably pivoted in said slot and engaging the feed-wheel, substantially as described.

5. A hand-drill-operating mechanism, comprising a stationary frame, a drill-socket journaled therein, means for rotating said socket including an oscillating lever pivoted upon said frame by a pivot parallel to and at one side of the drill-socket, and positively-operated adjustable feeding mechanism actuated from said lever, substantially as described.

6. A hand-drill-operating mechanism, comprising a drill-socket, means including an oscillating lever pivoted to one side of the drill-socket for rotating said socket, a threaded sleeve forming a part of the drill-feeding mechanism, a ratchet-wheel attached thereto, a shaft forming an extension of the lever-pivot in the direction of the sleeve, an arm attached to its outer end, and a pawl attached thereto and engaging the ratchet-wheel, substantially as described.

7. A hand-drill-operating mechanism, comprising a drill-socket, a threaded sleeve forming a part of the feeding mechanism, means for rotating the drill including a lever pivoted to one side of the drill-socket, an axial shaft extending from said lever in the direction of the threaded sleeve, an arm connected to its outer end, and step-by-step rotative means acting upon the threaded sleeve and actuated from the said arm, substantially as described.

8. A hand-drill-operating mechanism, comprising a drill-socket, a threaded sleeve form-

ing a part of the feeding mechanism, means for rotating the drill including a lever pivoted to one side of the drill-socket, an axial shaft extending from said lever in the direction of 5 the threaded sleeve, a slotted arm fixed to the outer end of said shaft, a pawl adjustable in said slot, and a ratchet-wheel upon the thread-

ed sleeve and rotated by the said pawl, substantially as described.

JACOB RACICH.
